UNITED STATES PATENT OFFICE.

PIERRE PLANTINGA, OF CLEVELAND, OHIO.

COKE-OVEN.

1,304,597.

Specification of Letters Patent. Patented May 27, 1919.

Original application filed July 26, 1916, Serial No. 111,521. Divided and this application filed August 15, 1917. Serial No. 186,259.

To all whom it may concern:

Be it known that I, PIERRE PLANTINGA, a citizen of the United States, resident of Cleveland, county of Cuyahoga, and State 5 of Ohio, have invented new and useful Improvements in Coke-Ovens, of which the following is a specification, the principle of the invention being herein explained and the best mode in which I have contemplated 10 applying that principle, so as to distinguish it from other inventions.

My invention relates to coke ovens, and particularly to an improved structure of the walls thereof. The subject-matter of this 15 invention has been divided out from my pending application, Serial No. 111,521.

The object of the invention is to provide a coke oven installation in which the cracking of adjacent walls, due to the expansion 20 and contraction, is reduced to a minimum.

The annexed drawings and the following description set forth in detail certain means embodying my invention, the disclosed means, however, constituting but one of various mechanical forms in which the principle of the invention may be employed.

In said annexed drawings:

Figure 1 represents a section of a fragmentary portion of a coke oven installation 30 embodying my invention, taken in the planes indicated by the lines I—I, in Fig. 3, the greater portion of such planes being parallel with the floor of the retort; Fig. 2 represents a transverse vertical section taken in the plane indicated by the line II—II, in Fig. 1 and viewed in the direction indicated by the arrows; Fig. 3 represents a transverse vertical section taken in the plane indicated by the line III—III, in Fig. 1 40 and viewed in the direction indicated by the arrows; Fig. 4 represents a fragmentary transverse vertical section taken in the plane indicated by the line IV—IV, in Fig. 1 and viewed in the direction indicated by the arrows.

Referring generally to some elements of my improved coke oven, with which the specific improvements herein claimed are utilized, there is provided an outer casing or 50 housing 1 of the required dimensions, such dimensions depending upon the number and size of the coking chambers, as will be readily understood. Formed within the casing 1 are a plurality of inclined coking chambers 55 2 whose sides, top and bottom are formed of suitable tile 3 abutting and joined with each

other, the joints formed by the tile elements running in the general direction, that is, parallel with the direction of inclination of the chambers, and at right angles thereto, 60 as shown in Figs. 2 and 3. The upper end of each such coking chamber 2 is closed by means of a suitable removable closure 4 and communicating with said upper or rear end is a charging duct 5 closed by a suitable 65 closure 6, as shown in Fig. 2. Each coking chamber 2 is furthermore provided with a vertical gas take-off flue 7 connected with a suitable pipe 8 for conducting the gases formed to the desired point. The lower or 70 front end of each chamber 2 is closed by means of a suitable removable closure 9, as shown in Figs. 1 and 2.

The coal is charged through the charging duct 5 into the chamber and when the coking operation is complete, the closures 4 and 9 are removed and the contents removed by pushing the same from the rear out from the front end, as will be readily understood.

Adjacent to each side of each coking chamber 2 is a set of parallel combustion chambers 10, these chambers also being inclined and having a direction of inclination parallel with that of the general direction of inclination of the coking chambers 2, 80 as shown in Fig. 3. The specific structure of the walls of these combustion chambers 10, in combination with a certain relative structure of partition walls hereinafter more fully described, forms the subject-matter 85 of this application.

Referring again generally to certain features of this coke oven, particularly described and claimed in said pending application No. 111,521, there is provided a vertical flue 11 with which the upper or rear ends of each of the combustion chambers 10 comprising a given set communicate, which flue 11 in turn communicates with a horizontal flue 12, which leads to the stack (not shown). This flue 12 receives and takes off the gases of combustion formed in the combustion chamber. The efflux of the gases of combustion from the flues 11 and 12 is valve regulated, as plainly shown and described 105 in said pending application. There is provided a longitudinal air duct 13, Figs. 2 and 3, which communicates by means of horizontal passages 14 with a vertical duct 15. The air duct 13 is usually connected with a recuperator (not shown) such as is ordinarily provided in this class of devices, as will be 110

readily understood. One such duct 15 is located between the front ends of each two adjacent sets of combustion chambers 10, as shown in Fig. 1, and communicates with a plurality of air inlets 16, Fig. 3, one of which is located adjacently to the lower end of each combustion chamber. These air ducts 16 are controlled by adjustable valves so that the influx of air at these points is capable of regulation. An additional air inlet 17 is provided, as shown in Fig. 3, which is also valve controlled. This last-named air inlet 17 communicates directly with the horizontal passage 14. Opposite the lower end of each set of combustion chambers 10 is a vertical flue 18, whose lower end communicates with a gas duct 19 which itself is connected with a suitable source of fuel gas (not shown).

The device as above described operates as follows, as has been explained in detail and claimed in said pending application:

The gas from the duct 19 flows upwardly into the duct 18 and becomes mixed with air from the inlet 17. Additional air from the inlets 16 is mixed with the mixture of air and gas first formed and is then burned. These gases of combustion pass up through the combustion chambers 10 and flow out through the flues 11 and 12. During such passage they heat the sides of the coking chambers 2 and effect the coking operation.

Between each two adjacent sets of combustion chambers 10 is disposed a partition wall 20 contiguous to the tile 3, that is, abutting the walls of the combustion chambers, Figs. 1 and 4, whose construction will now be described in detail, and forms, in combination with the relative construction and disposition of the side walls of the combustion chambers 10, the subject-matter of this application:

This partition wall 20 is built of suitable brick and the joints are made to run horizontally and vertically. It will thus be seen that the joints of these partition walls and the joints of the adjacent side walls of the combustion chambers 10 lie in planes which intersect one another, the arrangement, therefore, being such that the adjacent joints "break" with each other. By means of this arrangement, the cracking of these adjacent walls is minimized, as will be understood.

Attention will also be directed to the fact that the side walls of the coking chambers 2 diverge and that this divergence with respect to all the walls, as plainly shown in Fig. 1, is in the same direction. A part of the partition walls 20, as is shown in said figure, are rectangular in horizontal section, but certain of these walls, as for instance walls 21, are built so that their sides diverge in the direction opposite that of the direction

of divergence of the coking chambers 2, as shown. By providing such a wedge-shaped partition wall 21 at suitable intervals also contiguous to the walls of the adjacent combustion chambers, the rectilinear form of the entire installation may be preserved. This last mentioned arrangement, shown in this application, has also been specifically shown and described and claimed in said pending application.

By the means hereinbefore described and hereinafter claimed, exemplified in a coke oven of the general construction herein indicated, I have provided means whereby the cracking of the adjacent walls is reduced to a minimum.

What I claim is:

1. In a coke oven, the combination with a combustion chamber having its side walls constructed of joined elements; of a partition wall contiguous to one side of said combustion chamber and also constructed of joined elements, the elements of both of said walls being arranged to extend in different directions, whereby the joints of the respective walls will lie in planes intersecting each other.

2. In a coke oven, the combination with an inclined combustion chamber having vertical side walls constructed of joined elements, the joints formed by said elements extending in the direction of general inclination of the chamber and at right angles thereto; of a partition wall contiguous to one wall of said combustion chamber and also constructed of joined elements, the joints formed by the latter being horizontal and at right angles thereto.

3. In a coke oven, the combination with a pair of combustion chambers; of a partition wall disposed therebetween, said wall and those sides of said chambers contiguous thereto being constructed of joined elements, the elements of said wall being arranged to extend in directions different from those in which the elements of the sides of said chambers extend, whereby the joints of adjacent walls will lie in planes intersecting each other.

4. In a coke oven, the combination with a pair of inclined combustion chambers; of a partition wall disposed therebetween, those sides of said chambers contiguous to said wall being constructed of joined elements whose joints extend in the direction of general inclination of the chambers and at right angles thereto, said partition wall being also constructed of joined elements, the joints of the latter, however, being horizontal and at right angles thereto.

Signed by me, this 7th day of August, 1917.

PIERRE PLANTINGA.
